UNITED STATES PATENT OFFICE.

LEWIS G. LANGSTAFF, OF NEW YORK, N. Y.

DESIGN FOR A VESSEL FOR DISPENSING LIQUIDS.

No. 39,232.

Specification for Design.

Patented March 31, 1908.

Application filed January 29, 1906. Serial No. 298,544. Term of patent 7 years.

To all whom it may concern:

Be it known that I, LEWIS G. LANGSTAFF, a citizen of the United States, and resident of the borough of Brooklyn, in the city and State of New York, have invented a new, original, and ornamental Design for a Vessel for Dispensing Liquids, of which the following is a specification, reference being had to the accompanying drawing, forming a part thereof.

My new, original and ornamental design for a vessel for dispensing liquids is shown in the accompanying drawing, in which

Figure 1 is a top plan view of my vessel for dispensing liquids, and Fig. 2 is a side view of the same.

I claim:

The ornamental design for a vessel for dispensing liquids, as shown.

LEWIS G. LANGSTAFF.
